UNITED STATES PATENT OFFICE.

FRANK W. EDWARDS, OF CHICAGO, ILLINOIS, ASSIGNOR TO THE OHIO INJECTOR COMPANY OF ILLINOIS, OF CHICAGO, ILLINOIS, A CORPORATION OF ILLINOIS.

PROTECTOR FOR WATER-GAGES.

1,272,640.

Specification of Letters Patent. Patented July 16, 1918.

Application filed July 5, 1917. Serial No. 178,656.

To all whom it may concern:

Be it known that I, FRANK W. EDWARDS, a citizen of the United States, residing at Chicago in the county of Cook and State of Illinois, have invented a certain new and useful Improvement in Protectors for Water-Gages, of which the following is a full, clear, and exact description.

This invention relates to means for inclosing the glass tubes of water gages for use on steam boilers in such manner that in the event of the breaking of the tube the flying glass and escaping steam cannot come into injurious contact with the engineer or other person in the vicinity.

The objects of the invention are, first, to provide such an inclosing means or protector that it may be removed bodily from the gage without disturbing the gage connections with the boiler; second, to render the interior readily accessible for repairs and cleaning, and third, to counteract tendencies to spread apart.

The invention consists, as hereinafter more fully explained and claimed, of a protector or shield preferably made as a three-sided frame, having glazed openings, the panes of glass being fitted in pockets in the frame and held therein by removable strips of metal extending lengthwise of the frame and serving as clamps to hold the panes in place in a substantially leak-tight way.

The invention also consists, likewise as hereinafter more fully explained and claimed, of a gage glass holder of skeleton form adapted to receive the protector or shield last referred to in such way as to admit of the bodily removability of the protector or shield without disturbing the boiler connections of the holder, and coöperating with the protector or shield so as to tie them together longitudinally and brace them laterally.

In the accompanying drawings illustrating the invention, in the several figures of which like parts are similarly designated, Figure 1 is a side elevation; Fig. 2 is a longitudinal section, and Fig. 3 is a cross-section on line A B, Fig. 2, of a protector showing one embodiment of the principle and construction of the invention. Fig. 4 is a cross-section of the skeleton holder, and Fig. 5 is a cross-section of the glazed frame, both

views being taken in the same plane as Fig. 3. Fig. 6 is a perspective view of the exhaust connection. Fig. 7 is a perspective view of the skeleton holder with the glass gage tube in place. Fig. 8 is a perspective view of the glazed frame.

The glazed frame constituting the protector or shield, as shown detached in Figs. 5 and 8, has the three pocketed sides 1, 2 and 3, each having an opening 4. The side 1 may have the lamp brackets 5 extending horizontally therefrom. Each pocketed side is closed at top and bottom. The frame is open at the point opposite side 2 and its adjacent edges are provided with the outwardly extending longitudinal taper flanges 6. The top and bottom of the frame are provided with openings 7. The side or front 2 has the lugs 8 extending one above and the other below and perforated for the passage of fasteners to secure the frame to the holder. In the pocketed sides are placed the glass panes or strips 9 so as to close the openings. These panes are preferably heavy and specially made. These panes are secured in the pockets by longitudinal metal strips 10 arranged inside the frame and adapted to engage the edges of adjacent panes, and held in place by screws 11 screwed into them from outside the frame. These clamping strips may be provided with lateral wings as shown in Fig. 2, or they may be of uniform width throughout or of any other construction that requires the removal of all of their fastening screws in order to remove the panes of glass. In order to afford flat rests for the screw heads the angles between the sides may have the seats 12, and these seats may be screwthreaded to receive the screws.

The frame composed of the parts described, excluding of course the clamping strips 10, screws, and glass, may be and preferably is a single unitary casting, and with its panes of glass in place may be applied to and removed from the holder bodily.

The holder may be variously constructed, but a simple and efficient holder is herein shown as comprising a back 13 provided with the forwardly extending longitudinal taper flanges 14 to coöperate with the like flanges 6 of the frame; the top and bottom seats 15 to coöperate with the top and bottom openings of the frame; the tubular

bosses 16 to receive the water gage glass tube 17 and counterbored and screwthreaded to receive the boiler connections, only the upper boiler connection 18 being shown; the 5 two horizontally extending screwthreaded projections 19 and the taper dovetail 20 to receive the flange 21 of the exhaust tube 22. The back 13 is provided with an opening 23 and the exhaust tube's flange 21 is also 10 provided with a registering opening 24 for the escape of fine particles of glass and the free steam resulting from the breaking of the water glass.

The water glass may be set steam and 15 water tight in the bosses 16 by means of gaskets 25 or other packing means.

As will be observed by reference especially to Figs. 7 and 8, both the holder and the glazed frame are self-contained, and the 20 latter is capable of being bodily applied to and removed from the holder.

The glazed frame is applied to the holder by slipping it in between the bosses 16 so that its top and bottom openings register 25 with and engage the seats 15 on said bosses and the flanges 6 engage the flanges 14, and then the frame and holder are united by means of screws or bolts 26 applied to the lugs 8 and engaging the screwthreaded projections 19. Preferably lock-washers 27 are 30 interposed between the heads of the screws or bolts 26 and the lugs 8 to prevent said screws or bolts from working loose. By thus positively connecting the glazed frame 35 with the holder at top and bottom, a very secure tie is made that prevents the bosses 16 from spreading when under pressure. The flanges 6 and 14 so interlock as to brace the frame against spreading laterally. Thus 40 provision is made to meet all of the exigencies of service. The metal-to-metal fit of the parts of the frame and the holder is such that no packing is required to make the device substantially steam tight.

45 The broken glass and the steam entering the exhaust connection 22 is conveyed away by the pipe 28.

While I prefer to use a three-sided glazed frame, I do not restrict my invention there- 50 to, but reserve the right to use a glazed frame having any number of sides. And so also other variations in construction are esteemed to be within the spirit and scope of my invention.

55 What I claim is:—

1. In a protector for water gages, a frame having in one piece a number of pocketed sides closed at top and bottom, and also having glazed longitudinal openings, the 60 panes of glass being arranged in said pockets, and one piece strips running lengthwise of the panes of glass inside the frame and engaging the edges of adjacent panes, and screws mounted in the frame and en- 65 gaging the said strips.

2. In a protector for water gages, a one-piece three-sided frame having pockets projecting laterally therefrom, and an open back, panes of glass in said pockets, longitudinally arranged strips engaging the inside edges of adjacent panes of glass, and means to fasten said strips in place to clamp the panes of glass in position. 70

3. In a protector for water gages, a one-piece three-sided frame having pockets projecting laterally therefrom and an open back, said pockets being open outside and inside and closed at top and bottom, panes of glass in said pockets, longitudinally arranged strips engaging the inside edges of adjacent panes of glass, and screws engaging the frame and strips to clamp the panes of glass in position. 80

4. In a protector for water gages, a one-piece glazed frame having laterally offset 85 pockets closed at top and bottom and provided with longitudinal openings which are covered by the panes of glass, and an open back provided with longitudinal taper flanges extending the length of the frame, 90 combined with a holder having complementary longitudinal taper flanges engaging therewith.

5. In a protector for water gages, a one-piece three-sided frame having pockets projecting laterally therefrom, and an open back provided with longitudinal taper flanges to engage a suitable holder, panes of glass in said pockets, longitudinally arranged strips engaging the inside edges of adjacent panes of glass, and means to fasten 100 said strips in place to clamp the panes of glass in position. 95

6. In a protector for water gages, a self-contained protecting frame having top and bottom openings, and a self-contained holder provided with end bosses adapted to receive a gage tube, and seats on said bosses adapted to receive the protecting frame by slipping it in bodily between the bosses. 110

7. A protector for water gages, comprising a glazed frame having openings at top and bottom and an open back flanked by longitudinal taper flanges, and a holder for said glazed frame having the gage glass, top and bottom bosses provided with seats to fit in and close the open top and bottom of the frame, and a back provided with longitudinal taper flanges to coöperate with the flanges of the frame to brace the frame 115 against lateral spreading.

8. A protector for water gages, comprising a glazed frame having openings at top and bottom and an open back flanked by longitudinal taper flanges, and a holder for said glazed frame having the gage glass, top and bottom bosses provided with seats to fit in and close the open top and bottom of the frame, and a back provided with longitudinal taper flanges to coöperate with the 125 130

flanges of the frame to brace the frame against lateral spreading, said frame having lugs at top and bottom and the holder having projections at top and bottom, and 5 means to connect said lugs and projections to tie the top and bottom bosses together and to unite the frame and holder.

In testimony whereof I have hereunto set my hand this 2nd day of July A. D. 1917.

FRANK W. EDWARDS.
